United States Patent Office

Des. 182,869
Patented May 27, 1958

182,869

CLOCK OR SIMILAR ARTICLE

Samuel Ayres, Jr., Marblehead, Mass., assignor to General
Electric Company, a corporation of New York

Application July 9, 1957, Serial No. 46,873

Term of patent 14 years

(Cl. D42—7)

Fig. 1.

Fig. 2.

Fig. 3.

Fig. 4.

Fig. 1 is a front perspective view of a clock embodying my new design;

Fig. 2 is a front elevational view of the clock shown in Fig. 1;

Fig. 3 is a top plan view of the clock shown in Fig. 1; and

Fig. 4 is a side elevational view of the clock shown in Fig. 1.

The back of the clock is substantially plain.

I claim:

The ornamental design for a clock or similar article, substantially as shown and described.
